COMBINED ROSE AND ATTACHING COLLAR

Fred J. Russell, 8635 Otis St., South Gate, Calif.

Filed Mar. 31, 1964, Ser. No. 79,281

Term of patent 14 years

(Cl. D50—6)

FIG. 1.

FIG. 3.

FIG. 4.

FIG. 2.

I claim:

The ornamental design for a combined rose and attaching collar, as shown.
